ELECTRIC SWITCH

William Major, Cicero, Ill., assignor to Oak Manufacturing Company, Chicago, Ill.

Application June 22, 1934, Serial No. 731,835

8 Claims. (Cl. 200—11)

This invention relates to electric switches, particularly to those types useful for operating on a large number of circuits. For example, in radio receivers adapted to receive on a number of different broadcast bands it is desirable that a number of circuits be simultaneously switched. Devices of this character must be simple, cheap, compact and maintain good contact at the switch points. This is particularly important in radio receivers on account of the minute potentials involved and the introduction of noise due to faulty contact surfaces. Because of the requirements of different manufacturers, it is necessary at times to change the characteristics of a switch and in order to do this with a minimum of cost, it is necessary that the parts be so designed that changes may be made without requiring a change in the tooling equipment necessary for quantity production of a switch.

An object of this invention is to devise a switch which will satisfy the above requirements and which will be mechanically simple and cheap to make.

Referring to the drawing, Figure 1 is a plan view of the switch embodying this invention. Figure 2 is a sectional view on 2—2 of Figure 1. Figure 3 is a detail view. Figure 4 shows a rotor blank and Figure 5 shows a completed rotor.

The switch comprises an insulating disc 1 of bakelite or similar rigid material, preferably of a circular contour.

Disposed at regular intervals around the periphery are a plurality of stationary contacts 2 and 3, rigidly maintained in place by rivets 5. Contact 2, which is of one type, has an upstanding lug portion 6 perforated at 7, into which a wire may be soldered. Contact 2 also has an upstanding portion 8 terminating in a spring portion 9 at right angles to upstanding portion 8, from which depends a contact portion 10. Contact portion 10 has its sides 11 suitably bent outwardly so that a generally convex surface is presented to the interior region.

Contact 3 is similarly provided with a lug 12, perforated at 13 for connection to a wire. Contact 3 also has an upstanding portion 15 provided with an overlying portion 16 terminating in a bent contact edge 17. It will be noted that the sides of contact edge 17 are rounded at 18 so that a smooth curved surface is presented.

Carried in the center of disc 1 is a bushing 20 within which is mounted a shaft 21. The end of shaft 21 is milled at 22 so that a generally rectangular shape is secured.

An insulating rotor 25 of bakelite or the like

and comprising a circular disc is rigidly fastened at 22, such as by the square aperture therein fitting over shaft end 22 and thereafter flattening out the end of shaft 22 over the rotor 25.

Disposed around the edge of rotor 25 are a plurality of metallic contact segments 30, 31 and 32. While three segments are shown, it is evident that any number desired may be used, each of any angular extent. Each contact segment is rigidly fastened to rotor 25 by any suitable means such as rivets 34. It will be noted that the inner edge of each contact segment is provided with a plurality of slots 36, leaving inwardly extending tongues 37. If desired, certain of the tongues may be omitted to leave a gap 38, the purpose of which will be apparent later.

The outer edge of each of the contact segments has a plurality of regularly spaced inwardly directed curved notches 40, disposed around the periphery thereof.

As is evident from Figure 2, stationary contact 2 of which any number may be provided, has its contact portion 10 abutting the edge of the contact segments. Rotation of shaft 21, causing rotor 25 to turn, will result in the contact segments being turned past the active contact face 10 of stationary contact 2.

By virtue of the cooperation of the curved slot 40 and the curved shape of contact 10 it is clear that rotor 25 will tend to assume any one of a number of stable positions. Thus contact 10 bearing against the rotary contact members not only provides a continuous contact which may be useful for grounding purposes or the like but also provides a step by step stop-action of the switch.

The overhanging portion 16 of contact 3 extends over the contact segments and cooperates with the inwardly extending tongues 37 of the segments.

It is clear that where gaps 38 occur, no contact with member 3 will result. In this manner, by properly selecting the number and position of contacts 2, 3 and gaps 38—as well as the angular extent of the rotary contact segments a large number of different switching combinations may be provided.

In order to provide suitable limits between which the switch may be operated, an aperture 41 is provided in rotor 25. A pin 42 is forced in said aperture 41. A series of apertures 43 is provided in stator 1, said apertures being disposed in circular formation around the rotor axis and with radius equal to the distance of pin 42 from the rotor center. A pair of pins 44 may be dis-

5

40

45

50

55

posed in any two of said apertures 43 and function as stops for pin 42 in the rotor. Hence, by determining the location of pins 44, the extent of motion of the rotor may be simply and easily determined.

5 What is claimed is:

1. An electric switch comprising a stator having a plurality of fixed contacts mounted thereon in circular formation, a rotor disposed concentric with said fixed contacts, said rotor comprising an insulating base, a plurality of metallic segments of general circular shape concentrically disposed on said base, said segments being coplanar and being separated from each other, and having inner and outer edges, one of said edges on said segments being serrated, certain of said fixed contacts cooperating with said serrations to make contact therewith and to define a rotor position, others of said fixed contacts sliding over the sides of said segments to make contact therewith.

10 2. The structure of claim 1 wherein said segments have their outer edges serrated.

15 3. The structure of claim 1 wherein the non-serrated edges of said segments are provided with projections which projections are adapted to be contacted by the others of said fixed contacts.

20 4. The structure of claim 1 wherein the segments have their outer edges serrated and the inner edges are provided with projections which are adapted to be contacted by the others of said fixed contacts.

25 5. An electric switch comprising a flat insulating disk having an aperture therethrough, a series of spring contacts carried by said disk equidis-

tant from said aperture, a shaft rotatively mounted in said aperture, a flat insulating rotor disk carried by said shaft, a plurality of flat segmental contact members disposed on their flat side carried by said rotor, said members being disposed on the arc of a circle concentric with said shaft and being separated and insulated from each other, one of the edges of all of said members having regularly spaced indentations, certain of said stator contacts having spring portions pressing 10 against said indentations for simultaneously effecting contact and indexing, other of said stator contacts having a spring portion bent so that the edge thereof presses against the flat side of said rotor contacts.

5

15 6. The switch of claim 13 wherein the outer edge of said rotor contacts carries the indentations.

20 7. The switch of claim 5 wherein the other edge of said rotor contacts is adapted to have tongues projecting in the plane of the contact at predetermined positions and wherein certain stator contacts have their active edge cooperating with said tongues only for obtaining a selective action.

25

25 8. The switch of claim 5 wherein the outer rotor contact edge is indented and wherein the inner edge has tongues projecting inwardly toward the center in the plane of the contacts at predetermined positions and for a predetermined extent, and wherein certain stator contacts have their active edges cooperating only with said tongues for obtaining a selective switch action.

WILLIAM MAJOR.

CERTIFICATE OF CORRECTION.

Patent No. 2,014,624.

September 17, 1935.

WILLIAM MAJOR.

It is hereby certified that error appears in the printed specification of the above numbered patent requiring correction as follows: Page 2, second column, line 16, claim 6, for the reference claim number "13" read 5; and that the said Letters Patent should be read with this correction therein that the same may conform to the record of the case in the Patent Office.

Signed and sealed this 5th day of November, A. D. 1935.

Leslie Frazer

(Seal)

Acting Commissioner of Patents.
